UNITED STATES PATENT OFFICE.

JAMES OGG, OF PAHALA, TERRITORY OF HAWAII.

CENTER-FINDER.

1,105,917.

Specification of Letters Patent.

Patented Aug. 4, 1914.

Application filed January 5, 1914. Serial No. 810,337.

To all whom it may concern:

Be it known that I, JAMES OGG, a subject of the King of England, residing at Pahala, in the Province of Kau and Territory of Hawaii, have invented new and useful Improvements in Center-Finders, of which the following is a specification.

This invention relates to a center finding tool.

10 The object of the present invention is to provide a simple, easily operated, convenient tool to be used by machinists and other mechanics for finding or maintaining the center within a cylinder or like device, when lining up machinery, and which is also useful for laying out work or flanges and like parts.

20 The invention consists of the parts and the construction and combination of parts 25 as hereinafter more fully described and claimed, having reference to the accompanying drawings, in which—

Figure 1 is a perspective view of the center finding tool. Fig. 2 is an end view 25 of a cylinder or flange showing the application of the tool for the purpose of locating the same. Fig. 3 is a cross section on line X—X, Fig. 2.

30 Referring to the drawings, A indicates a flat bar, dovetailed in cross section, upon which is slidably mounted a pair of fan-shaped plates 2 and 3 provided with upwardly extending lugs 4 and 5. The lugs 4 and 5 have threaded openings formed 35 therein adapted to receive a right and left-hand threaded screw 6. The screw 6 is provided with a fixed nut 7 by which it may be turned.

35 The bar A is provided with a center hole 8, and the nut is provided with a plurality of perforations 9 which extend through the nut and screw and are also adapted to be brought into alinement with the center hole 8, being always held in alinement by a lug 40 45 formed on the bar A and extending into a groove 11 formed on the nut.

The tool may be placed within the interior of the cylinder or flange and adjusted in position to find the center thereof by 50 turning the nut 7, with connected screw 6, until the plates 2 and 3 have been moved out on the bar A into a position where their outer contacting points 12 have engaged with the interior surface of the flange or cylinder. The center of the cylinder is 55 thus quickly found and may also be main-

tained by leaving the center finding tool in the position shown in Fig. 2. The outer contact points of the plates 2 and 3 may also be recessed, as indicated at 13, and may thus be placed on the surface of the end of the cylinder or flange for the purpose of finding the center, as indicated in Fig. 2. Any one of the several openings 9, formed in the nut 7, may be brought into alinement 60 with the center hole 8 of the bar A and a sight may thus be taken through that hole which registers with the center opening on the object to be lined up with. It can thus be seen that a perfect alinement of a cylinder, with relation to the crank-shaft of the machine, may be quickly secured, as the center finding tool may be easily placed in position. Similarly a center may be maintained and worked from for other purposes, 75 such as patterns and the like.

The tool constructed as here shown is neat in appearance, simple and substantial in construction and may be quickly adjusted, with relation to any diameter of circle 80 or opening, by simply turning the nut in the desired direction to either expand or contract the contacting points 12 of the plates 2 and 3. The materials and finish of the several parts of the device are such 85 as experience and judgment of the manufacturer may dictate.

Having thus described my invention, what I claim and desire to secure by Letters Patent—

1. A center finding tool comprising a bar having a center opening formed therein, a pair of plates slidably mounted on said bar, lugs formed on the plates, a right and left-hand threaded screw extending through 95 said lugs, and a fixed nut on said screw, having a plurality of openings extending therethrough, any one of which may be brought into alinement with the center opening.

2. A center finding tool comprising a bar having a center opening formed therein, a pair of plates slidably mounted on said bar, lugs formed on the plates, a right and left-hand threaded screw extending through 105 said lugs, a fixed nut on said screw having a plurality of openings extending therethrough, an annular groove formed in the nut, a projecting lug extending into said groove formed on the bar, and means for holding the plates on the bar.

3. A center-finding tool, comprising a

bar having a center opening formed therein, a pair of fan-shaped plates slidably mounted on said bar with the flared ends of the plates outermost, lugs formed on the inner 5 ends of said plates, a right and left-hand threaded screw extending through said lugs to move the plates in unison, a fixed nut on said screw having a plurality of openings extending therethrough, any one 10 of which may be brought into alinement

with the center opening, and recessed seats formed in the outer corners of the fan-shaped plates, substantially as described.

In testimony whereof I have hereunto set my hand in the presence of two subscribers. 15

JAMES OGG.
